US0D1004088S

(12) **United States Design Patent** (10) Patent No.: **US D1,004,088 S**
(45) Date of Patent: ** Nov. 7, 2023

(54) **SURGICAL STAPLE**

(71) Applicant: **Medline Industries, LP**, Northfield, IL (US)

(72) Inventors: **Ryan Niver**, Glenview, IL (US); **Scott A. Goldstein**, Deerfield, IL (US); **Wesley Reed**, Libertyville, IL (US)

(73) Assignee: **Medline Industries, LP**, Northfield, IL (US)

(**) Term: **15 Years**

(21) Appl. No.: **29/804,413**

(22) Filed: **Aug. 19, 2021**

(51) LOC (14) Cl. **24-02**

(52) U.S. Cl.

USPC **D24/145**

(58) **Field of Classification Search**

USPC **D24/145, 155**

CPC **A61B 17/0642; A61B 17/0644; A61B 17/064; A61B 17/068; A61B 17/0682; A61B 2017/0641**

(57) CLAIM

The ornamental design for a surgical staple, as shown and described.

DESCRIPTION

FIG. 1 is a front perspective view of a first embodiment of our new surgical staple;

FIG. 2 is a top plan view of the surgical staple of FIG. 1; FIG. 3 is a bottom plan view of the surgical staple of FIG. 1;

FIG. 4 is a front side elevational view of the surgical staple of FIG. 1, the rear side elevational view being identical;

FIG. 5 is a right side elevational view of the surgical staple of FIG. 1, the left side elevational view being identical;

FIG. 6 is a front perspective view of a second embodiment of our new surgical staple;

FIG. 7 is a top plan view of the surgical staple of FIG. 6; FIG. 8 is a bottom plan view of the surgical staple of FIG. 6;

FIG. 9 is a front side elevational view of the surgical staple of FIG. 6, the rear side elevational view being the mirror image thereof;

FIG. 10 is a right side elevational view of the surgical staple of FIG. 6;

FIG. 11 is a left side elevation view of the surgical staple of FIG. 6;

FIG. 12 is a front perspective view of a third embodiment of our new surgical staple;

FIG. 13 is a top plan view of the surgical staple of FIG. 12; FIG. 14 is a bottom plan view of the surgical staple of FIG. 12;

FIG. 15 is a front side elevational view of the surgical staple of FIG. 12, the rear side elevational view being identical;

FIG. 16 is a right side elevational view of the surgical staple of FIG. 12, the left side elevational view being identical;

FIG. 17 is a front perspective view of a fourth embodiment of our new surgical staple;

FIG. 18 is a top plan view of the surgical staple of FIG. 17; FIG. 19 is a bottom plan view of the surgical staple of FIG. 17;

FIG. 20 is a front side elevational view of the surgical staple of FIG. 17, the rear side elevational view being identical;

FIG. 21 is a right side elevational view of the surgical staple of FIG. 17; and,

FIG. 22 is a left side elevation view of the surgical staple of FIG. 17.
